INTERNAL CUSHIONED TOOL-AND-CHUCK LOCK FOR POWER HAMMERS

John J. Roberts, Louisville, Ky.

Application July 26, 1937, Serial No. 155,586

1 Claim. (Cl. 279—19.7)

My invention relates to improvements in the ways and means designed for the ready installation and efficient holding of collared chucks or tool-bits in their service places in power-hammers; and the objects of my invention are: first, to devise a lock for a collared chuck or tool-bit, adapted to be clasped around either of them and adapted to hold them securely in their operative positions in the nozzle and cap of the power-tool, hammer or drill, in which the lock is adapted to fit; second, to provide a helical compression spring designed to fit on over the smaller part of the cylindrical chuck-lock and adapted to slide back against the shoulder of the integral head of the lock to hold the lock in its service place in the nozzle of the power-tool; third, to produce a combination of nozzle and nozzle-cap adapted to hold said chuck, chuck-lock and cushion-spring in their relative service positions when operatively assembled therein; fourth, to devise for said nozzle and nozzle-cap a spring-pressed detent easily operative and adapted to lock the nozzle-cap in its service position on the nozzle until released by the operator; and, bearing in mind the necessary variation of speed and power of stroke required in the average workman's power hammer to render it practicable in general service; I have a still further object in my invention, namely, to design in my new lock for said collared chuck or bit an elongated head provided with a plurality of annular grooves around the inside thereof adapted to receive the collar which surrounds the chuck or bit, so that in the same hammer the shank, at the option of the operator, may be set in the operative zone of the reciprocating hammer-head, high for receiving the short and necessarily light and fast strokes for calking and scaling and lower for receiving the longer, and, necessarily slower and heavier strokes, for stone-chipping and riveting, which usually require heavier blows than the work of calking or scaling.

In my present invention I have attained these objects in the practical mechanism illustrated in the accompanying drawing which forms a part of this specification, in which Figure I is a plan view of a cross section of the nozzle, chuck-shank and cap-detent of a power-hammer, cut in the horizontal plane at the broken lines 1', 1', of Figs. II and IX. The dotted circle in Fig. I indicates the relative location of the counterbore of the nozzle shown in Fig. II. Figure II is a longitudinal section through the middle of the nozzle, nozzle-cap and the lower part of the casing of a power-hammer, including a collared bit-chuck, partly in section and partly in elevation and all

its contiguous and coacting parts, all shown in their relative positions, set for the longest and heaviest strokes of the operating hammer-head. Fig. III is a plan view of the top of the head of one of the similar halves of said chuck-lock. Fig. IV is an elevation of the inside of one of the halves of said chuck-and-bit lock, showing the annular grooves in the elongated head. Fig. V is an elevation of the outside of one of the similar halves of the chuck-and-tool lock. 10

Fig. VI is a side elevation of a fragment of a collared drill-bit and one of the halves of said bit-lock shown in its normal operative position. Fig. VII is a side elevation of a collared chuck adapted to work in combination with said chuck-lock, as shown in Figs. II and IX. Fig. VIII is a side elevation of the nozzle-cap adapted to service in connection with said chuck-and-tool lock and coacting parts, as shown in Figs. II and IX. 15

Figure IX is a longitudinal section through the middle of the nozzle, nozzle-cap and the lower part of the casing of a power hammer, including a collared bit-chuck, partly in section and partly in elevation with all its contiguous and coacting parts, all shown in their relative, operative positions, set for the shortest and lightest strokes of the operating hammer-head. 20

Fig. X is a plan view of the top of the internal cushion-spring; and Fig. XI is a side elevation of said cushion-spring. Fig. XII is a plan view of the top of the steel abutment-block installed in the top of the counterbore in the nozzle; and Fig. XIII is a side elevation of said steel abutment block. 25

In the following detail description of my invention, as illustrated in the accompanying drawing, similar characters refer to similar parts throughout the several views. 30

The hammer-nozzle 1 may be fastened by means of screws to the lower part of the hammer casing 2 in which there would be ample room for any kind of mechanism adapted to operate the hammer-head, the lower part 7 of which is shown in Figs. II and IX. 35

The tool-and-chuck lock, or divided collet is composed of two similar halves. One half 4 of the said chuck-lock is shown in Fig. II in its service position holding the chuck 5 in its operative position by means of the collar 5a imbedded in the lower annular groove 4a of the chuck-lock. The other similar half designated as 4, also, has been removed to enable the inner parts, the annular grooves, 4a, 4a, and other parts, to be seen in this view. The threaded plug 1y holds the detent 1a installed in the boring 1x. The lower end of 45

the nozzle 1 is threaded and adapted to receive the threaded nozzle-cap 3 screwed back to the shoulder of said nozzle. Now, installed in said shoulder is a detent 1a adapted to be actuated by 5 means of a compression spring 1b installed behind the detent. And in the smooth face of the upper end of the nozzle-cap 3 is a small hole 3b into which the lower end of the spring-pressed detent, 1a, springs when the nozzle-cap has been 10 screwed back on the nozzle as far as it should go. This detent prevents said cap from unscrewing until the operator lifts the detent back out of the retaining hole, 3b, using the notch 1z. Below the head of the chuck-lock, the lower 15 portion 4b thereof is smaller and adapted to slip-fit into the helical cushion-spring 6, as shown in Fig. II, where the lower end of the spring 6 rests upon the bottom of counterbore in the cap 3 and the upper end of said spring 20 abuts against the shoulder of the chuck-lock, 4, 4. Consequently, it may be seen that when the chuck 5 is installed with its collar 5a set in the lower annular groove 4a, the end of the chuck-shank upon which the hammer-head 7 is 25 adapted to strike, is set low under the hammer-head, as shown in Fig. II; and the following strokes would be heavier than they would be when the chuck-shank is set high, as shown in Fig. IX, because the operative zone of the hammer-head 7 is much longer than the zone of operation shown in Fig. IX. And, assuming that the hammer-head 7, is operating in both instance under the same pressure, we shall find that each 30 of the longer strokes, as shown in Fig. II, would consume more time and a greater momentum would be developed in each stroke, when compared with the shorter hammer strokes, as shown in Fig. IX.

The cylindrical chuck 5 has a collar 5a adapted 40 to fit into the annular grooves, 4a, 4a, of the chuck-lock, 4, 4, to hold the chuck 5 in its operative position when assembled; and the hexagonal chuck-shank 5b has facets adapted to slip-fit through the hexagonal mortise 11b in the 45 abutment block 11 and the hexagonal mortise in the nozzle 1, to prevent the rotation of the chuck. The chuck 5 has, also, been provided at its lower end with a comparatively long, axial, 50 tapered boring 5x having a uniform predetermined gradient and adapted to furnish an adequate bearing for different sizes of bits having shanks with similar tapers. And through the middle of said axial boring run two transverse 55 drift-pin holes at right angles to each other. The lower hole 5y is drilled through the chuck 5 midway between the ends of said boring and is adapted for drifting out the tapers 8a of the shanks 8 of the large bits, as shown in Fig. II; 60 and the upper hole 5z is drilled through the chuck 5 at the upper end of said axial boring and is adapted for drifting out the tapers 9a of the smaller bits 9 whose smaller tapers 9a must necessarily go deeper into said tapered boring to get an adequate chuck-bearing, as shown 65 in Fig. IX.

The upper drift-pin hole 5z would be sufficient 70 for drifting out tapers of all sizes of bits; but in this case, the tapers of the large bits would have to be unnecessarily long to reach the upper drift-pin hole, which is inside the nozzle-cap 75 3 and, consequently, the cap and spring must be removed before we can use the upper drift-pin hole. For these reasons, for large bits, it is better to have, also, the lower drift-pin hole 5y,

which is conveniently situated below the nozzle-cap 3.

The nozzle-cap 3 is adapted with knurled rings, 3a, 3a, for screwing on or off with the hands. And if we are using this power hammer very 5 much as a stone-drill, we may use a stone-drill whose shank is finished like the shank of chuck 5, as illustrated in Fig. VI where the cylindrical shank 10 is adapted to slip-fit in the chuck-and-bit lock 4, 4, and the collar 10a is designed to fit 10 in the annular grooves 4a, 4a, of said bit-lock; while the hexagon part 10b of the shank of the drill is made to slip-fit through the hexagonal mortise 11b in the abutment block 11. By using 15 a stone-drill whose shank is so fabricated, we can work without the chuck 5.

In the long cylindrical head of the chuck-and-bit lock, 4, 4, the annular grooves, 4a, 4a, are made much wider than the thickness of the 20 chuck-collar 5a, for the purpose of allowing the chuck a certain amount of unimpeded movement forward and backward in its service action. For when we are working with a power hammer provided with this tool-and-chuck lock, drilling or chipping stone, we, of course, push hard on the power hammer to hold the cutting bit to its work; and this pressure causes a back thrust 25 of the chuck 5 which forces the collar 5a up against the upper part of the groove 4a, if it be set in one of the lower grooves, as shown in Fig. II, or up against the abutment block 11, if the chuck-collar 5a should be set in the upper annular groove 4a, as shown in Fig. IX. And in either case, the steel abutment block 11 held in 30 place by means of the retaining screw 11a, receives the back-thrust of the chuck 5 while the power tool is in action.

Now, if we desire to change the chipping hammer chuck 5 shown in Fig. II, for the drill shown 35 in Fig. VI, we use a drift-pin in the hole 5y to remove the bit 8 from the chuck 5. Then we unscrew the nozzle-cap 3 with the hand and remove from the nozzle the chuck 5, with the chuck-lock 4, 4, and the cushion-spring 6. Then we slip the spring off the chuck-lock and the 40 two separate parts, 4, 4, of the chuck-lock unclasp from the chuck 5 and its collar 5a. And these parts, 4, 4, we clasp about the drill-shank 10 and its collar 10a; the collar fitting into the middle groove 4a for a medium stroke; and then 45 we slip the cushion-spring 6 over the smaller portion 4b of the bit-lock and place them up into the counterbore of nozzle 1, pushing the hexagonal part 10b of the drill-shank up through the abutment block 11 until the head of the bit-lock 50 impinges against the abutment block 11. We then screw the nozzle-cap 3 back on nozzle 1 until the detent 1a springs into the hole 3b in the rim of the cap 3, which locks the cap on 55 securely. And the mechanism is ready for service. 60

Having described my invention and the ways and means of using it, I claim:

In a power-hammer having a reciprocating hammer-head and operating mechanism enclosed 65 in a casing, a nozzle; an axial boring through the nozzle; a nozzle-cap mounted on said nozzle; an axial boring of predetermined size in the nozzle-cap in alignment with the axial boring in said nozzle; a counterbore in the nozzle-cap, 70 whose walls form a coincident continuation of the walls of the counterbore in the nozzle; in combination with a tool-and-chuck lock, comprising duplicate, cylindrical halves of a split sleeve, the upper portion thereof, serving as a 75

head, being larger than the remaining lower portion and adapted to slip-fit in said counterbores, and the lower portion thereof, being adapted to slip-fit in the axial boring of the nozzle-cap; a collared shank of a bit-chuck adapted to fit in said tool-and-chuck lock; a plurality of similar, annular grooves around the inside of the head of said tool-and-chuck lock, adapted to hold the collar of said shank high or low in
10 normal operation for adjusting the speed and

power of stroke of said hammer by changing the zone of operation of said hammer-head; and a helical compression spring fitting in the lower end of said cap-counterbore and adapted to slip-fit over the lower portion of said tool-and-chuck lock to hold the lock in its service position, said spring being adapted, also, to cushion the hammer-blows on the mechanism, when the bit-chuck is empty.

JOHN J. ROBERTS. 10
